UNITED STATES PATENT OFFICE.

CHARLES F. ROOT, OF CLEVELAND, OHIO, ASSIGNOR TO THE CHANDLER & PRICE COMPANY, OF CLEVELAND, OHIO, A CORPORATION OF OHIO.

PRESS-FEEDING MECHANISM.

Application filed February 8, 1923. Serial No. 617,819.

The present improvements relate to that type of sheet feeding device which is primarily adapted for use with so-called Gordon or platen printing presses. The object of the invention is to provide a sheet feeding device for use in the connection stated that may be readily attached to existing presses with little or no alteration in their structure and that, when attached or installed, will not unduly encumber the press or be in the way of the operator. The device or machine is designed to pick up and transfer the sheets by pneumatic suction and the invention has as a further object the controlling of such suction conjointly with the movement of the picker fingers so as to locate the sheets accurately on the platen of the press. Still another object of the invention is to render the mechanism simple and compact and to reduce the number of operating parts so that the requirements in the way of attention and repair may be reduced to a minimum.

To the accomplishment of the foregoing and related ends, said invention, then, consists of the means hereinafter fully described and particularly pointed out in the claims, the annexed drawings and the following description setting forth in detail certain mechanism embodying the invention, such disclosed means constituting, however, but one of various mechanical forms in which the principle of the invention may be used.

In said annexed drawings:—

Fig. 1 is a side elevation showing my improved sheet feeding mechanism as attached to a press of the type in question, the latter being shown in this, as well as in the succeeding figures, in dotted outline only; Fig. 2 is a front elevation of such mechanism and press; Fig. 3 is a plan view of the mechanism with portions of the press only appearing; Fig. 4 is a broken vertical section of the upper and lower ends of the vertical tubular shaft that constitutes the main supporting element of the mechanism, the plane of such section being indicated by the line 4—4, Fig. 3; and Fig. 5 is a transverse section of another detail, the plane of the section being indicated by the line 5—5, Figs. 2 and 3.

The press illustrated in the drawings, as

previously indicated, is of the familiar platen or Gordon type and need not be further described than to note the oscillatorily mounted platen 1 on which the sheet requires to be placed preliminarily to being brought into contact with the form by the conjoint movement of such platen and of the opposite bed 2, which carries such form in a suitable chase, not shown. In the several general views appearing in the drawings, the press is shown with the platen in its sheet-receiving position, the grippers 3, whereby the sheet is held onto the platen during the printing operation, being suitably raised.

As previously indicated, the member, which constitutes the principal support of the feeding mechanism of present interest, is a vertical tubular shaft or column 5 which as shown, is preferably installed on the left-hand side of the main frame of the press so as to lie laterally adjacent to the platen in its aforesaid sheet-receiving position, rising a suitable distance thereabove. The manner in which said shaft is attached to the frame of the press is a matter of indifference, but in the illustrative construction shown (see Fig. 1) I utilize a plate 6 that is adapted to be directly bolted against the corresponding side frame of the press, such plate being provided with two lugs or brackets 7 and 8 in which the shaft is fixedly held at vertically spaced points. In order to insure the necessary rigidity, a third bracket 9 connects the upper portion of the shaft directly with an adjacent point of the aforesaid side frame.

The present feed mechanism is designed to operate in conjunction with a magazine or table 10 for the blank sheets that is located directly in front of the platen and is inclined downwardly in a direction away from such platen at an angle sufficient to cause the stack of paper to rest in a correspondingly inclined position against a back plate 11 on said table. Such back plate is longitudinally movable along the top of the table to advance the stack as successive sheets are removed from the front thereof, but inasmuch as the table forms no part of the present invention, it is not deemed necessary to illustrate the means for accomplishing such movement or for vertically adjusting the elevation of the table.

as may be desirable in order to bring the stack into proper registering position for the operation of the feeding mechanism proper.

5 Fixedly mounted on and closing the upper end of the tubular shaft 5 is a hollow cap-piece 15 provided with a radially projecting arm 16, likewise hollow, said arm being provided with a tubular extension 17
 10 disposed approximately at right angles to the median line of the platen. Rotatably mounted in such tubular extension 17 is a hollow shaft 18, the respective ends of which project beyond the corresponding
 15 ends of said extension, such shaft being sealed save for an interior connection with the passageway in the arm 16 and the connection now to be described with the suction fingers that are carried by the end of said
 20 shaft that lies over the plate. The sheet engaging and moving members in the form of suction tips 20, shown as two in number, are carried by telescoping tubular arms 21 that are attached to a hollow shaft 22 oscillatory mounted in the end of a hollow arm 23 fixedly attached and forming a part of said shaft 18, the interior of which, it will thus be seen, is in free communication
 25 with the arms 21 and thus with the suction
 30 tips 20.

Oscillation of said shaft 18, as well as conjoint but independently controlled oscillation of the shaft 22, is derived from a transverse driving shaft 25 journaled in suitable bearings 26 on the main frame of the press, the right-hand end of said shaft, as viewed in Fig. 2, being connected by means of suitable gears 27 with the so-called large gear 28 of the press. Said shaft 25, it will
 40 thus be seen, is rotated in unison with the movements of the various parts of the press, including platen 1. At its opposite end, the left, as viewed in said Fig. 2, shaft 25 carries two cams 29 and 30, such first-named
 45 cam being formed with a cam groove 31 in its outwardly directed face, while cam 30 is a face cam, its inwardly directed face projecting varying amounts from the vertical plane at different points about its periphery.

Pivoted to plate 6 at a point intermediate of shaft 5 and said cam 29 is a bell crank lever 32, one arm of which carries a roller 33 that engages such groove 31 in said cam, while the other arm is connected by means of a rod 34 with a lever arm 35 that projects rearwardly from tubular shaft 18. Rotation of said cam 29 will accordingly be effective to rock said shaft 18 through the arc indicated by the full line and dotted positions wherein said lever arm 35 is shown in Fig. 1.

Oscillatory mounted alongside of shaft 5 in suitable bearings 36 and 37, the former projecting from cap-piece 15 and the latter

from the lug or bracket 7 in which said shaft itself is mounted, is a shaft 38, the lower end of which is provided with a forwardly projecting arm 39 that has its outer end bent downwardly so as to press against the operative face of cam 30. The upper end of said shaft 38 carries a lever arm 40, carrying a fork 41, that is adapted to remain in operative connection with the corresponding end of a bar 42 reciprocably held in guides 43 projecting upwardly from shaft 18, irrespective of the oscillation of the latter produced in the manner just described above. A compression spring 44 interposed between one of said guides 43 and a collar 45 on bar 42 tends normally to move the latter towards the right, as viewed in Fig. 2, and at the same time, by virtue of the connection between the outer end of said bar and lever arm 40, said spring serves to retain the operating lever 39 at all times against face cam 30. The action of this cam, in other words, will be to move the rod or bar 42 to the left against such spring 44 as the end of lever 39 rides up the cam and then to permit reverse movement of said bar as such lever end rides down again.

The inner end of bar 42 is flattened out and formed with an inclined face 46 and pivotally attached to shaft 18, adjacent to such end of the bar, is a lever 47 that is held against such face by means of a tension spring 48 connected at one end to the lever in question and at the other end to a fixed arm 49 rising from shaft 18 to the rear of the bar 42. A link 50 in turn connects lever 47 with a lever 51 attached to the corresponding end of the tubular shaft 22 that carries the suction tip arms 21. From the construction last described it will follow that reciprocation of the bar 42 to the right, as viewed in Figs. 2 and 3, will cause oscillation of said shaft 22 so as to depress the suction tips 20, due to the action of spring 48 in pulling up on lever 47 so as to hold same at all times against cam face 46. Conversely, movement of the bar 42 in the opposite direction, i. e. to the left, as viewed in the figures just referred to, will rock said lever 47 and thus shaft 22 in the opposite direction so as to lift the suction tips 20 or swing the same in a clockwise direction, as viewed in Fig. 1. The pivotal connection between link 50 and lever 51 is provided by means of a pin and slot, as shown in Fig. 5, or equivalent lost-motion device, so that the lever and thus suction tips 20 may have a limited movement independently of the actuating means just described; a tension spring 52 serving normally to depress said tips as far as permitted by such lost-motion device.

Vertical shaft 5, which constitutes the main supporting element of the mechanism, is tubular, as has already been explained,

and reciprocably mounted within the same is a second tubular shaft 55 that in its elevated position is adapted to communicate with the suction tips 20 through a port 56 near its upper end and the passages in the interconnecting parts. A flexible suction line 57 is connected through a suitable coupling with the lower end of said shaft 56 and as a result it will be seen that reciprocation of said shaft serves alternately to apply suction to said tips, and, as the upper end of said shaft drops below and so uncovers the passage in arm 16, to relieve such suction due to the ingress of air at atmospheric pressure. Reciprocation of said shaft 55, which thus constitutes in effect a valve, is derived from the same shaft 25 as are the movements of the other parts of the mechanism, a lever 57 pivoted intermediate 20 of its ends to plate 6, having one such end connected with the shaft, while the other is provided with a roller 59 that rides on the edge of cam 30, such edge being made of varying radius so as to oscillate said lever 25 in synchronism with the movements of the other parts of the mechanism.

The operation of the machine as a whole should be apparent from the foregoing description of the construction and operation 30 of its several component parts. In order to set the machine for such operation, a sheet of paper of the size to be handled is laid on platen 1 in proper position. Then shaft 25 is rotated to swing rock shaft 18 through the medium of bell crank lever 32, connecting rod 34 and lever arm 35, and at the same time to lower sucker tip arms 21 through the medium of lever 39, oscillatory shaft 38 and connections between the upper end of the 40 latter and the tubular shaft 22 that carries said arms, so that the latter will lie in substantially parallel relation to the platen, as shown in full lines in Fig. 1.

It will be noted that both arm 23 and the two arms 21 are angular in shape and that they all lie in approximately parallel planes with the angles in said arms 21 directed oppositely to that in said arm 23. It will also be noted that the angularly related 50 parts of arms 21 are independently longitudinally adjustable, so that said arms 21 may be adjusted so as to bring the sucker tips 20 in correct position near the lower or inner edge of the sheet.

The height of the table 10, that supports 55 the stack of blank sheets, is next adjusted so that when through further rotation of shaft 25 the sucker tips are brought into operative relation with the foremost sheet on such stack, as shown in dotted outline in Fig. 1, they will contact with such sheet in exactly the same relation to the lower edge thereof as was determined by adjustment of said tips with respect to the sheet on the platen. 60 Assuming the valve 56 is open when the suc-

tion tips are thus in position to contact with the foremost sheet of the stack, the action of the several cams will be first to swing the arms 21 outwardly sufficiently to cause such sheet to clear the table 10; then to rock 70 shaft 18 so as to lower the sheet through a downwardly curving path positioned directly over the platen; and finally to swing arms 21 downwardly until the sheet is brought into contact with the platen. Following the 75 foregoing sequence of movements, the air suction is thereupon cut off, leaving the tips free to be raised, whereupon they are swung back again into registering position with the stack. 80

As a result of my improved construction, the suction tips, it will be seen, may be moved independently of the oscillation of the main shaft 18 from which such tips are supported, while the path of both the feeding and return movements of such tips may be varied as desired by properly designing the corresponding cam. 85

Other modes of applying the principle of my invention may be employed instead of the one explained, change being made as regards the mechanism herein disclosed, provided the means stated by any of the following claims or the equivalent of such stated 90 means be employed. 95

I therefore particularly point out and distinctly claim as my invention:—

1. In mechanism of the character described, the combination with means adapted to support a stack of sheets in approximately vertically arranged position in front of the printing couple of a platen printing press, of a horizontally extending support; a member oscillatorily mounted on such support 100 and having its free end movable transversely of the latter in a general vertical direction; a second member provided with a sheet engaging and moving finger, said second member being oscillatorily mounted in turn on said first member at a point removed from the latter's axis of oscillation so as to be adapted in the raised position of said first member to press such finger against the foremost sheet on such stack and in the lowered 105 position of such first member to deposit such sheet in an approximately horizontal plane; and means adapted thus to oscillate said members independently of each other. 110

2. In mechanism of the character described, the combination with means adapted to support a stack of sheets in approximately vertically arranged position in front of the printing couple of a platen printing press; of a horizontally extending support; a member oscillatorily mounted on such support 120 and having its free end movable in a plane lying transversely of the latter; a second member provided with a sheet engaging and moving finger, said second member being 125 130

oscillatory mounted in turn on said first member at a point removed from the latter's axis of oscillation so as to be adapted in the raised position of said first member to press such finger against the foremost sheet on such stack and in the lowered position of such first member to deposit such sheet in an approximately horizontal plane; and means adapted thus to oscillate said members independently of each other.

3. In mechanism of the character described, the combination with means adapted to support a stack of sheets in approximately vertically arranged position in front of the printing couple of a platen printing press; of a horizontally extending support; a member oscillatory mounted on such support and having its free end movable in a plane lying transversely of the latter; a second member provided with a sheet engaging and moving finger, said second member being oscillatory mounted in turn on said first member at a point removed from the latter's axis of oscillation and extending reversely from its own axis towards the latter's axis so as to be adapted in the raised position of said first member to press such finger against the foremost sheet on such stack and in the lowered position of such first member to deposit such sheet in an approximately horizontal plane; and means adapted thus to oscillate said members independently of each other.

4. In mechanism of the character described, the combination with means adapted to support a stack of sheets in approximately vertically arranged position in front of the printing couple of a platen printing press; of a suitable support; a horizontally extending rock shaft journaled at one end in said support; a transverse arm carried by said shaft; a member provided with a sheet engaging and moving finger and movably attached to said arm at a point removed from said shaft so as to be adapted in the raised position of said first member to press such finger against the foremost sheet on such stack and in the lowered position of such first member to deposit such sheet in an approximately horizontal plane; and means adapted to rock said shaft and move said members independently of each other.

5. In mechanism of the character described, the combination with means adapted to support a stack of sheets in approximately vertically arranged position in front of the printing couple of a platen printing press; of a suitable support; a horizontally extending rock shaft journaled at one end in said support; a transverse arm carried by said shaft; a second arm provided with a sheet engaging and moving finger and oscillatory attached to said first arm at a point removed from said shaft so as to be adapted in the raised position of said first member to

press such finger against the foremost sheet on such stack and in the lowered position of such first member to deposit such sheet in an approximately horizontal plane; and means adapted to rock said shaft and move said members independently of each other.

6. In mechanism of the character described, the combination with means adapted to support a stack of sheets in approximately vertically arranged position in front of the printing couple of a platen printing press; of a suitable support; a horizontally extending rock shaft journaled at one end in said support; a transverse arm carried by said shaft; a second arm provided with a sheet engaging and moving finger and oscillatory attached to said first arm at a point removed from said shaft, said second arm extending reversely from its own axis towards the axis of said first arm so as to be adapted in the raised position of said first member to press such finger against the foremost sheet on such stack and in the lowered position of such first member to deposit such sheet in an approximately horizontal plane; and means adapted to rock said shaft and move said members independently of each other.

7. In mechanism of the character described, the combination with a suitable support, a horizontally extending rock shaft journaled in said support, a transverse arm carried by said shaft, a second arm provided with a suction finger and oscillatory attached to said first arm at a point removed from said shaft, and means adapted to rock said shaft and oscillate said second arm independently of each other, the means for thus oscillating said second arm including a member reciprocably mounted on said shaft so as to move in unison therewith.

8. In mechanism of the character described, the combination with a suitable support, a horizontally extending rock shaft journaled in said support, a transverse arm carried by said shaft, a second arm provided with a suction finger and oscillatory attached to said first arm at a point removed from said shaft, and means adapted to rock said shaft and oscillate said second arm independently of each other, the means for thus oscillating said second arm including a member reciprocably mounted on said shaft so as to move in unison therewith, a cam on said member, a lever pivoted to said shaft and engaging with said cam, another lever on said second arm, and a link connecting said levers.

9. In mechanism of the character described, the combination with a suitable support, a horizontally extending rock shaft journaled in said support, a transverse arm carried by said shaft, a second arm provided with a suction finger and oscillatory attached to said first arm at a point removed

- from said shaft, and means adapted to rock said shaft and oscillate said second arm independently of each other, the means for thus oscillating said second arm including 5 a member reciprocably mounted on said shaft so as to move in unison therewith, an inclined cam face on said member, a lever pivoted to said shaft, resilient means retaining said lever in contact with said cam face, 10 another lever on said second arm, and a link connecting said levers.
10. In mechanism of the character described, the combination of a vertically extending main support, a cap-piece on said support having an arm, a horizontally extending rock-shaft journaled in such arm, a lever fixed to the end of said shaft adjacent said support, means connected with said lever adapted periodically to rock said 20 shaft, a transverse arm fixed to the other end of said shaft, a second arm provided with a suction finger and oscillatorily attached to said first arm at a point removed from said shaft, a member reciprocably 25 mounted on said shaft so as to move in unison therewith, said member being operatively interconnected with said second arm to oscillate same, and means adapted to reciprocate said member irrespective of the 30 rocking of said shaft.
11. In mechanism of the character described, the combination of a vertically extending main support, a cap-piece on said support having an arm, a horizontally extending rock-shaft journaled in such arm, a lever fixed to the end of said shaft adjacent 35 said support, means connected with said lever adapted periodically to rock said shaft, a transverse arm fixed to the other end of said shaft a second arm provided with a suction 40 finger and oscillatorily attached to said first arm at a point removed from said shaft, a member reciprocably mounted on said shaft so as to move in unison therewith, said member 45 being operatively interconnected with said second arm to oscillate same, and means adapted to reciprocate said member irrespective of the rocking of said shaft, said means including a lever oscillatorily mounted on 50 said cap-piece and having a fork engaging one end of said member.
12. In mechanism of the character described, the combination of a vertical tubular main support, a cap-piece on said support having a tubular arm communicating 55 with the interior of said support, a horizontally extending tubular rock-shaft journaled in said arm, a suction finger carried by said rock-shaft and connected with the interior thereof, and a second tubular shaft connected 60 with a suction line and movably mounted within said support, said shaft having a port adapted in one position of said shaft to register with the passage in said arm and such passage being left open to atmosphere 65 in another position of said shaft.
13. In mechanism of the character described, the combination of a vertical tubular main support, a cap-piece on said support having a tubular arm communicating with the interior of said support, a horizontally extending tubular rock-shaft journaled in said arm, a suction finger carried by said rock-shaft and connected with the interior thereof, and a second tubular shaft connected 70 with a suction line and reciprocably mounted within said support, said shaft having a port adapted in one position of said shaft to register with the passage in said arm and such passage being left open to atmosphere 75 in another position of said shaft.
14. In mechanism of the character described the combination of an oscillatory arm, a second arm provided with a suction finger and oscillatorily attached to said first arm at a point removed from the axis of oscillation thereof, and means adapted to oscillate said arms independently of each other, said means including a lost-motion connection. 80
15. In mechanism of the character described, the combination of an oscillatory arm, a second arm provided with a suction finger and oscillatorily attached to said first arm at a point removed from the axis of oscillation thereof, and means adapted to oscillate said arms independently of each other, the means for thus oscillating said second arm including a lost-motion connection. 85
16. In mechanism of the character described, the combination of an oscillatory arm, a second arm provided with a suction finger and oscillatorily attached to said first arm at a point removed from the axis of oscillation thereof, and means adapted to oscillate said arms independently of each other, the means for thus oscillating said second arm including a lost-motion connection, and resilient means normally tending 90 to depress such suction finger as far as permitted by such connections. 100
17. In mechanism of the character described, the combination of an oscillatory arm of angular shape, and a second arm provided with a suction finger and oscillatorily attached to said first arm at a point removed from the axis of oscillation thereof, said second arm extending reversely from its own axis and being likewise angular with its angularly related parts independently longitudinally adjustable, and said two arms lying in approximately parallel planes with the angles therein oppositely directed. 115
- Signed by me, this 6th day of February, 1923.

CHARLES F. ROOT.
